[57] CLAIM

The ornamental design for a combined garment form and hanger therefor, substantially as shown.

DESCRIPTION

FIG. 1 is a front elevational view of a combined garment form and hanger therefor illustrating my new design;

FIG. 2 is a side elevational view taken from the left of FIG. 1;

FIG. 3 is a side elevational view taken from the right of FIG. 1;

FIG. 4 is a top plan view thereof;

FIG. 5 is a bottom plan view thereof;

FIG. 6 is a rear elevational view thereof;

FIG. 7 is a cross-sectional view taken in the direction of the arrows on line 7—7 of FIG. 1;

FIG. 8 is a cross-sectional view taken in the direction of the arrows on line 8—8 of FIG. 1;

FIG. 9 is a cross-sectional view taken in the direction of the arrows on line 9—9 of FIG. 1.
